UNITED STATES PATENT OFFICE.

LEON EVANS, OF MEDFORD, OREGON.

CENTERER.

No. 863,909.

Specification of Letters Patent. Patented Aug. 20, 1907.

Application filed April 6, 1907. Serial No. 368,827.

To all whom it may concern:

Be it known that I, LEON EVANS, a citizen of the United States, residing at Medford, in the county of Jackson and State of Oregon, have invented new and

5 useful Improvements in Centerers, of which the following is a specification.

My invention pertains to devices designed for use in marking the centers of shafts and the like; and it consists in the peculiarly constructed, hollow-cone 10 centerer, hereinafter described and claimed, calculated to be used to advantage in marking the centers of round and square shafts of different sizes.

In the accompanying drawings, forming part of this specification: Figure 1 is an elevation of the centerer 15 constituting the preferred embodiment of my invention; the same being shown with its parts in their normal positions. Fig. 2 is a vertical section of the same with the marking pin partly in elevation. Fig. 3 is a vertical section showing by full lines the positions in 20 which the several parts are placed precedent to the propulsion of the marking pin, and by dotted lines the position which said pin assumes when forced or impelled forward by the spring back of the same. Fig. 4 is a transverse section taken in the plane indicated by 25 the line 4—4 of Fig. 2. Fig. 5 is an elevation showing the marking pin and the interior tube in which said pin is adapted to move, and: Fig. 6 is a transverse section taken in the plane indicated by the line 6—6 of Fig. 2.

30 Similar letters of reference designate corresponding parts in all of the views of the drawings, referring to which:

A is the upper and outer casing section of the centerer, which is closed at its upper end and open at its lower 35 end, and is provided in its side with a longitudinal slot a, and B is the lower and inner casing section. This latter is telescopically arranged in the section A, is open at its upper end, and is provided in its lower end with a central vertical, smooth bore b for a purpose presently 40 set forth. The said section B is connected to the section A through a screw c carried by section B and movable in the slot a of the section A; and its lower end d is reduced and exteriorly threaded for the detachable 45 connection of the interiorly threaded shank e of a hollow cone C through which extends an aperture f alined with the smooth bore b of casing section B. By virtue of the shank of the cone C being detachably connected to the lower end of casing section B, it will be observed 50 that the cone C may be expeditiously and easily removed and replaced with a larger or smaller cone, thus increasing the range of usefulness of the device.

D is the marking pin of the device. The lower portion f' of this pin is of a size to snugly fit the smooth bore b in casing section B and the aperture f in the cone 55 C, and the upper portion g is comparatively large in about the proportion illustrated, is stepped as shown,

and is provided with a radially disposed socket h, a radial pin i movable in said socket, and a coiled spring j arranged in the socket and back of the pin so as to press the latter outward.

60

E is the inner tube of the device which is open at its lower and upper ends and is longitudinally slotted at l to receive the pin i. The said tube E is fixed by a screw m in casing section A; and it snugly receives the upper, comparatively large portion g of the marking 65 pin D; and it also receives an upper, comparatively small coiled spring F, as shown.

Surrounding the marking pin D and interposed between the lower end of the tube E and the lower portion of the casing section B is a large coiled spring G, 70 the function of which will be presently pointed out in detail.

My novel centerer is used after the manner of an awl—that is to say, the user places the hollow cone C on the end of the shaft to be marked, keeping as near in 75 line as possible with the shaft, and presses the upper and outer casing section or handle A toward the shaft, in the same manner as an awl is forced into a piece of wood, until the marking pin D is heard to strike, when the center of the shaft will be found to be accurately 80 and positively marked.

At M in the upper and outer casing section A is an inclined portion designed to coöperate with the pin i, and with this in mind the operation of the marker will be fully understood from the following:

85

It will be seen that when the casing section A is forced downward, the tube E will be moved downward with it and the lower spring G will be compressed between the lower end of said tube E and the lower end portion of the casing section B, ready to return the said tube 90 and casing section A to their normal positions subsequent to a marking operation. It will also be seen that the spring G will cushion the downward movement of tube E and casing section A, and that by reason of the pin i on marking pin D engaging the upper 95 end of the casing section B, the spring F will be compressed between the upper end of said marking pin and the upper end of the casing section A until the inclined portion M of the casing section A engages and presses the pin i inward and clear of the end of casing section 100 B when the spring F will expand and forcibly impel the pin D downward to effect the marking. Then when pressure is removed from the upper end of the casing section A, it will be seen that the spring G acting against the lower end of the tube E will return said 105 tube, and the marking pin D and casing section A to their normal positions, and as soon as the pin i reaches a point above the upper end of the casing section B it will be forced outward by its spring and will assume a position above said end of section B ready for another 110 operation of the marker.

It will be gathered from the foregoing that pressure

exerted on the casing section A is all that is necessary to operate my novel centerer, and that when such pressure is removed the parts are automatically returned to their normal positions ready for another operation.

5 It will also be gathered that the centerer is simple, compact and inexpensive in construction and embodies no delicate parts such as are likely to get out of order after a short period of use.

Having described my invention, what I claim and 10 desire to secure by Letters-Patent, is:

1. A centerer comprising casing sections one of which is movable with respect to the other, a marking pin, springs respectively for moving said pin in opposite directions, means on the pin for engaging one casing section to enable the other casing section to put the spring back of the marking pin under tension, and means on such other casing section for disengaging the means on the pin from the first mentioned casing section.

2. A centerer comprising casing sections one of which is movable with respect to the other and is provided with an inclined portion, a marking pin, springs respectively for moving said pin in opposite directions, and a radial, spring-pressed pin carried by the marking pin and arranged to engage such other casing section and to be 25 engaged by the inclined portion of the first mentioned casing section.

3. A centerer comprising a casing section having a hollow cone and also having a smooth-bore, a casing section connected to and movable with respect to the first 30 mentioned section, a marking pin, a spring for returning

said pin to its normal position, a spring backing the marking pin and arranged to impel the same forward, and a spring-pressed, radial pin carried by the marking pin and arranged to bring up against the rear end of the first mentioned casing section and also arranged to be 35 engaged by the second mentioned casing section and disengaged from the first mentioned section.

4. A centerer comprising a casing section having a central, smooth bore, a hollow cone detachably connected to the casing section and having an aperture alined with the smooth bore thereof, a marking pin movable through said bore and aperture, and means for impelling the marking pin through said bore and aperture.

5. A centerer comprising an outer slotted casing section having an inclined portion, an inner casing section 45 telescopically arranged in the outer section and connected thereto by a port movable in the slot thereof and having a smooth bore, an interior, slotted tube secured in the outer casing section, a marking pin having an enlarged portion movable in said interior tube and also having a 50 radial, spring-pressed pin movable in the slot of the tube and arranged to bring up against the inner casing section and be engaged by the inclined portion of the outer casing section, a spring arranged between the forward end of the interior tube and the inner casing section, and a 55 spring arranged in said tube and back of the marking pin.

In testimony whereof I have hereunto set my hand in presence of two subscribing witnesses.

LEON EVANS.
